PLATE FEED AND STORAGE MEANS IN AN ADDRESSING MACHINE

Anton Renauer, Deisenhofen, near Munich, Germany, assignor to Rena Buromaschinen-Fabrik G.m.b.H. & Co., Deisenhofen, near Munich, Bavaria, Germany

Filed July 30, 1962, Ser. No. 213,437

Claims priority, application Germany, Aug. 4, 1961, R 30,878

2 Claims. (Cl. 101—47)

The present invention relates to an addressing machine in which the printing plates carrying the addresses are pulled out singly from a supply stack thereof disposed in an introduction chute, are conveyed along a horizontal guide path past a selected printing position and are laid off or deposited in a laying-off chute.

In addressing machines the printing plates carrying the addresses are mostly fed from a rather great stack by means of a holder means or drawer into a vertically disposed introduction chute. Said plates are conveyed, after printing, to a vertically disposed laying-off chute arranged at a deeper level. In both the introduction and laying-off chutes, the printing plates are stacked lying one on top of the other. Particularly, the nature and disposition of the laying-off chute influences essentially the constructional height of the addressing machine. Table mounted machines, without a special underframe to accommodate such prior laying-off chutes must include complicated, hence expensive, laying off means. It has been proposed to arrange the laying-off chute in an oblique position whereby the printed printing plates are arranged standing partially upright one behind the other. Even with such modification a substantial constructional height of the machine frame is still necessary, which height is still great for a practical table mounted machine. In the case of small hectographic type addressing machines it is also already known to arrange the laying-off chute in a horizontal manner, but in this case the print forms are laid off directly into this chute in the absence of any drawer or like receiving means and lying in a stack one atop the other. In such cases, quantities of the laid-off printing plates from time to time must be removed from the horizontal stack to make room for others.

The principal object of the present invention is to provide a table mountable addressing machine wherein the problems heretofore set forth are eliminated and wherein the printing plates are laid off in a stack while permitting the machine casing of the machine to have a low constructional height sufficient to enable the machine to be built without a special underframe.

The invention further provides a table mountable addressing machine wherein the laying-off chute is arranged in a horizontal manner in the machine casing and provides means in this chute whereby a drawer or carrier can be shifted laterally step-wise for receiving the stack of printing plates to be laid off and said printing plates are received in said carrier in an upright standing position one behind the other.

In order to pass the printing plates from their horizontally disposed path into a vertically upright standing position in the laying-off carrier, there is provided an opening in the guide path disposed over the laying-off chute on one side of the casing and there is further provided under the guide path, a tilting edge portion and a sheet metal guide extending downward and leading into the laying-off chute and the carrier.

In order to shift the drawer in the laying-off chute and in order thus to shift the laid off printing plates, there is provided, in the laying-off chute a movable pressure plate mounted for reciprocal movement synchronized with the printing plate transport means. The invention further

2

provides a spring-loaded claw disposed in the laying-off chute above the stack of printing plates and engageable with the last laid-off printing plate; said claw cooperates with the pressure plate to position the printing plates in an upright, standing arrangement.

Further features of the invention will become clear from the following description of an embodiment of the invention as shown in the accompanying drawing:

FIG. 1 is a perspective view of the addressing machine according to the invention.

FIG. 2 is a partial view of the printing plate lay-off device.

FIG. 3 is a sectional view taken along the line III—III in FIG. 2.

FIG. 4 is a sectional view taken along the line IV—IV in FIG. 2.

FIGS. 5 and 6 are sectional views similar to that of FIG. 4 but with the pressure plate shown in successive working positions.

Referring to FIG. 1, the addressing machine according to the invention comprises a box-shaped casing 1 with a low constructional height "a," so that the addressing machine can be used as a table mounted machine without necessitating the provision of a special underframe therefor.

On the plane upper surface 2 of the casing 1 there is mounted a vertical introduction chute 3, which is essentially flush with the right hand front side 4 of the casing 1. A plate holder means preferably in the form of a drawer 5 can be removably received in and shifted relative the introduction chute. Said drawer 5 is adapted to receive a pile or stack of printing plates arranged one above the other.

A horizontal carrying arm 6 is mounted to the introduction chute 3. The said arm 6 carries on its free extremity and enclosed in a casing 7, a flat counter pressure element (not shown) which is mountable for movement in a vertical direction. The pressure element or printing element which may be of conventional construction is disposed relative the top of casing 1 beneath the arm 6. A conventional humidifying device (not shown) may also be provided within the casing 1.

An example of such a pressure element is disclosed in U.S. Patent No. 2,015,552 issued September 24, 1935, to H. P. Elliot; although it is obvious that any other conventional printing member may be utilized.

A horizontal guide path 9 leads from the introduction chute 3 to the printing location 8 and extends beyond the printing point or location 8. Said guide path is covered by a covering rail 10, except at the printing spot 8. The covering rail 10 lies disposed parallel to and flush with the upper surface 2 of the casing 1.

Any type of conventional conveying device (not shown) which could if desired be similar to the conveying means disclosed in the aforesaid Elliot patent, pulls the printing plates 11 carrying the addresses singly from the introduction chute 3, conveys them continuously to the printing point or location 8 and finally to the end 12 of the guide path 9. Printing plates commonly utilized comprise framed typed originals in mirror image form.

In accordance with the invention, the printing may be applied freely on the upper surface 2 of the casing 1 by means of a conventional application device (not shown) and can be laid off by means of the laying-off device of the invention subsequent to the printing process.

Under the extremely 12 of the guide path 9 there is mounted normal to the guide path, a horizontally disposed laying-off chute 13 formed in the machine casing 1, said chute being freely accessible from the front side 14 of the casing 1. The left hand end or side 15 of the casing 1 closes off this laying-off chute at one side thereof. The said chute 13 is provided with guide rails 16 serving to

mount and guide a drawer 17 frictionally mounted thereon within the laying-off chute 13. The said drawer is adapted to receive the laid-off printing plates 11 in successive single steps. The printing plates 11 are laid-off from the path 9 vertically one at a time positioned upright one behind the other and arrange themselves upright in the drawer 17. The drawer 17 preferably has a configuration also to fit interchangeably into the introduction chute 3. In addition, said drawer provides storage space for storing the stacks of printing plates outside the machine.

In order to transfer the printing plates 11 from their horizontal position at the end 12 of the guide path 9 to their upright standing position in the laying-off chute respectively in the drawer 17 pushed into said chute 13, one guide rail 18 is positioned adjacent one side of the printing plate guide path 9 whereby same terminates adjacent and in front of the laying-off chute 13, while the other guide rail 19 extends farther than rail 18 to a superposed position over the laying-off chute 13 at the side thereof. Parallel to the guide rail 19 but somewhat below same, a depending L-shaped flange 20 formed of sheet metal, is secured at one elongated edge thereof to the under surface 2 at the casing 1 adjacent the opening 22. Integral with and depending from the opposite edge 20' of flange 20 is a downwardly depending slightly curved wall portion 21. There is provided on the opposite side of opening 22 a downwardly depending but upwardly curved sheet metal guide 22' extending downward into the laying-off chute 13, which guides 21 and 22' act to deviate the printing plate to cause same to tilt downward to a slightly inclined but vertical position (as shown in FIG. 4) in the drawer 17.

The printing plate 11, which has been guided into the position shown in FIG. 5 is acted upon by a pusher plate 23, which is mounted to a crank 26 for to and fro movement synchronous with the printing plate transport means (carrying arm 6 with its counter pressure element, guide path 9 and the conveyor device) in the arrow directions indicated in FIG. 6 to urge the plate 11 toward the group 11' of plates which have already been stacked in the drawer 17. The crank 26 may be pivotally mounted on the casing 1 on one of the walls of the chute 13 and is connected directly to the motor of the machine.

As the plate is moved across the chute 13 by pusher 23 the plate 11 assumes a vertically upright position. A stationary mounted spring-biased claw 24 has a hook position 25 which engages the last laid-off printing plate 11 and thus maintains the laid-off stack of print plates firmly in place in vertically upright position. The pressing plate 23 pushes in a stepwise manner against the drawer 17 as the pusher 23 engages a plate 11 as shown in FIGS. 5 and 6 and said drawer is filled gradually with printing plates 11 in the indicated arrow direction towards the exit of the chute 13. Before the arrival of a new printing plate 11, the pressing plate 23 returns in its starting position, as shown in FIGURE 4. As

is evident from the drawing (FIG. 1), the drawer 17 containing the laid-off plates 11 is accessible easily from the front side of the casing. Because the plates are stacked in an upright formation according to the invention with necessity for understructure is eliminated.

What I claim is:

1. In an addressing machine which includes a casing, an introduction chute for step-wise feeding of generally rectangular printing plates into a horizontal guide path, a printing station disposed along the guide path, a horizontally disposed laying off chute located at the terminal end of and beneath the guide path to receive said printing plates dropped one at a time from an enlarged opening in the terminal end of the guide path, said laying off chute communicating to the exterior of the casing, horizontal guide rail means in said laying off chute, and an open-topped plate receiving drawer frictionally engaged upon said guide rail means within said laying off chute, the herein invention comprising, means for effecting step-wise displacement of the drawer with the entry thereto of each printing plate from the terminal end of the guide path, said step-wise displacement being equal to the thickness of said printing plate, said means comprising stationary guide plate means within said laying off chute beneath the terminal end of the guide path for directing the printing plates one at a time from the guide path to a tilted position upon one edge thereof in the drawer, reciprocating pressure plate means arranged to engage a face of said printing plate immediately upon entry thereof into the drawer to move said plate to a vertical position and to then displace the drawer along the guide rail means a distance equal to the thickness of the printing plate, and spring biased hook means arranged centrally and above said laying off chute to engage the face of the printing plate to retain the plate in a vertical position when the pressure plate is caused to retract, the drawer thereby being automatically shifted step-by-step by each successive printing plate for the entire length thereof.
2. The structure as set forth in claim 1 in which said stationary guide plate means comprises a depending arcuate guide extension at one side of the terminal end of the guide path at the enlarged opening thereof and a downwardly depending flange having an edge portion disposed within said enlarged opening and adapted to tilt the edge of a printing plate dropping from the terminal end of the guide path.
